DENTAL MATRIX INSTRUMENT

Lewis H. Dvorak, Jacksonville, Fla.

Application May 18, 1950, Serial No. 162,705

15 Claims. (Cl. 32—63)

1

My invention relates to dental matrix instruments and particularly to an improved dental matrix band, and to improved apparatus for positioning, adjusting and retaining a dental matrix band.

A general object of my invention is to provide an improved dental matrix and improved matrix positioning, adjusting and retaining means.

Another object of my invention is to provide a dental matrix, together with matrix band positioning and adjusting means, which permits the positioning of the operative, filling-retaining portion of the matrix band in close and conforming relation to the cavitated portion of a tooth.

A more specific object of my invention is to provide devices which, in use, cause a matrix band to conform to and lie closely against a surface of a tooth, from the occlusal edge of the tooth to the gingival line.

The novel features which I believe to be characteristic of my invention are set forth with particularity in the appended claims. My invention itself, however, both as to its organization and method of operation, together with further objections and advantages thereof, may best be understood by reference to the following description taken in connection with the accompanying drawing, in which Fig. 1 is a top view of an instrument in accord with my invention, shown in operative association with a tooth to be filled; Fig. 2 is a side view of a portion of the instrument in position as in Fig. 1; Fig. 3 is a view of the side of a portion of the instrument opposite to the side shown in Fig. 2; Figs. 4 and 5 are sectional views taken along lines 4—4 and 5—5, respectively, of Fig. 1; Fig. 6 is an exploded perspective view showing in more detail certain parts of the instrument of Fig. 1; Fig. 7 is a top view of a portion of the instrument showing a modification in accord with my invention; and Fig. 8 is a perspective view of another part of the instrument in accord with a further modification.

Referring now to the drawing, the instrument is shown in Fig. 1 in position in association with two proximal molars 1 and 2. The cavity 3 in molar 1 is covered along the side of the tooth, by an operative portion of matrix band 4. The opposite end portions 5 and 6 of band 4 are attached to respective band-and-holding members 7 and 8 by wrapping the ends of the band about a portion of each member and by thereafter sliding a sleeve or cap over the member to lock the ends to the holding members as hereinafter described. The members 7 and 8 are internally bored and threaded and are disposed on a

2

threaded rod 9 in a manner such that by rotating the rod 9 in one direction the members 7 and 8, and the opposite band ends 5 and 6, are separated, and by rotation in the other direction, are drawn toward each other.

A rigid or semi-rigid clip or stiffening member 10 is disposed on an intermediate or central portion of the matrix band 4 and is so proportioned and arranged as not to pass through the interstice between teeth 1 and 2, and also to cause the band to lie against exposed sides or faces of the proximal teeth at opposite ends of the clip 10. The specific construction of clip 10 is further described in connection with Fig. 6, and a modified construction is shown in Fig. 8.

The members 7 and 8, which hold the respective ends of matrix band 4, and which are movable apart or together by appropriate rotation of the double threaded bolt or rod 9, are each provided with two protruding portions in the form of ears, the ears of member 7 being designated 11 and 12 and those of member 8 being designated 13 and 14. These ears are arranged to guide or press the matrix band 4 into conforming contact with the teeth as hereinafter further explained.

The matrix band 4 extends through the clip 10 and, from the left hand end of the clip as seen in Fig. 1, passes along and firmly engages substantially the whole side surface of tooth 1 which confronts tooth 2. This operative portion of the matrix band passes between tooth 1 and ear 11, and the end or terminal portion 5 of the band is passed through a central portion of the movable member 7 and finally bent back to be locked on member 7, a cap 15 being provided to slip over a part of member 7 more securely to maintain the attachment of end 5 to member 7.

The portion of matrix band 4 which extends from the right hand end of the clip 10, as seen in Fig. 1, passes along the side of tooth 2 which confronts tooth 1 and between tooth 2 and ear 13 of member 8, the end portion 6 of the band being attached to member 8 and held in position thereon by a cap 16, all in the manner heretofore described in connection with end portion 5 and member 7. Of course, this portion of the band in contact with tooth 2 is in operative position for use in filling a cavity, if one exists, in tooth 2 along the side confronting tooth 1.

Threaded rod 9 is provided at one end with an upset portion or rounded knob 17 which prevents member 7 from becoming inadvertently completely unscrewed from the rod, and it may also prevent the removal from the rod of cap 15 under

certain circumstances. The rounded end further serves to minimize the chance of damage to the mouth of the patient.

At the other end of the rod a knurled knob 18 is provided to permit rotation of the rod by the fingers. A sleeve 19 is shown on the rod between member 8 and knob 18. This sleeve may be loose on the rod or may be tight fitting, as desired. If loose fitting, the sleeve may be grasped by the fingers of one hand to hold the instrument in position while the knob 18 is being turned by the fingers of the other to adjust the separation of members 7 and 8. The instrument may be controlled without difficulty, however, even though sleeve 19 is entirely omitted; in which case rod 9 may be either threaded throughout its length or may be smooth and unthreaded throughout the portion, approximately, shown covered by the sleeve 19 in Fig. 1. It has been found desirable to prevent cotton from becoming tangled in the threads of the rod to attach the sleeve 19 to the cap 16, thereby to leave exposed the threaded portion adjacent knob 18 which is remote from the area in which cotton is normally used. It may be also desirable to attach a sleeve, similar to but shorter than sleeve 19, to cap 15 to extend over knob 17 and to cover the threads along the portion of the rod between holding member 7 and knob 17. If sleeves attached to caps 15 and 16 are so provided to cover the threads adjacent the tooth or teeth being filled, the sleeves may be pulled by the fingers to slide the caps off of members 7 and 8 when it is desired to change or adjust the matrix band as held by members 7 and 8.

Fig. 2 is a side view of the instrument in position on teeth 1 and 2 as in Fig. 1 and shows the relationship between the clip 10 and teeth 1 and 2. The lower edge of clip 10 lies close to or along the gingival line 19' and the top edge of the clip is at about the level of the occlusal surfaces of the teeth. The matrix band which extends through clip 10 is of slightly less width than the clip, the width of the band being measured in the direction from top to bottom of the tooth as shown, and it will be seen that neither the clip nor matrix band will interfere with normal closing of the jaw with the matrix band and clip in the position shown.

The view of the instrument in Fig. 3 is taken from the side opposite the teeth and clearly shows ears 12 and 14 of members 7 and 8, respectively. It is to be noted that the slot between ear 12 and the adjacent edge of cap 15 of member 7 is inclined from the vertical, as is the slot between ear 14 and cap 16 of member 8. The inclination in each instance is such that a matrix band having end portions extending, respectively, through these slots and locked in place under caps 15 and 16 will be so held as to have the lower edges of the opposed portions of the band adjacent the respective ears 12 and 14 further apart than the upper edges. The ears 11 and 13, shown in other figures, and the slots formed between these ears and caps 15 and 16, respectively, are similarly inclined.

Accordingly, whether the matrix band is positioned on the one side of the instrument for use on teeth of the lower left jaw as shown in Fig. 1 or on the other side for use on teeth of the lower right jaw, that edge of the matrix band which is toward the gingival line will be pulled into engagement with the divergent surfaces of the adjacent teeth near the gingival line. This desired result is obtained by the foreshortening effect of

the divergently inclined slots formed by ears 11 and 13, or 12 and 14, depending on the side of the instrument on which the matrix band is positioned, and by the trapezoidal shape of the clip 10 as seen in Fig. 2.

It will be apparent that certain portions of the instrument which are seen in several figures have been similarly numbered in each instance, and it is unnecessary to repeat a description thereof for each figure. Thus, for example, it is to be understood that the hereinabove descriptions of rod 9, knob 17 and sleeve 19 apply to the view of the instrument as seen in Fig. 3 in the same manner as to the views of Figs. 1 and 2.

Turning now to Fig. 4, which is a partially sectional view taken along line 4-4 of Fig. 1, the band 4 is seen to lie closely against the face of tooth 1 to form a wall across the cavity 3. The member 7 is shown in end view and comprises ears 11 and 12 and legs 20 and 21. End portion 5 of matrix band 4 is inserted behind ear 11 and extends along the inner face of leg 20 to be folded back at the far end being taken as that toward rod 9 and the outer face being that toward tooth 1. Cap 15 is in position to maintain the extreme end of portion 5 against the outer face, thereby to lock the end of the band to member 7. It is to be noted that ear 11 is so shaped as to press the edge of band 4 which lies near the gingival line against the surface of the tooth 1. Since teeth are smaller near the gingival line than at the occluding surface, ear 11 extends from the bottom of member 7 toward the tooth and is then bent upwardly and slightly backwardly toward the center of member 7. The curve of the upwardly extending portion of ear 11 is such as to conform as nearly as practicable to the shape of the tooth. The material of which member 7 is made is preferably slightly resilient and is deformable by pliers to take a permanent set. Thus the ears, such as ear 11, may be bent by pliers into substantially the correct configuration, and the resilience will permit the ears thereafter to tend to adjust themselves to exactly the proper shape when the band is in place and tightened against the teeth.

Clip 10, as shown partially in cross section in Fig. 4, comprises a central portion 22, a folded-over top portion 23 and an upturned ear portion 24. The matrix band passes between portions 22 and 23, and the arrangement is such as to hold clip 10 firmly to band 4 and thereby to provide a matrix band having a portion approximately midway between the ends of increased bulk, stiffness or rigidity, this portion corresponding to the part crimped between the folded portions 22 and 23 of the clip 10. It may prove desirable under some circumstances more firmly to attach clip 10 to the intermediate portion of band 4 by the use of solder or cement or in other known ways, and it is also practical to construct the matrix band of a single piece of metal with an intermediate portion of greater rigidity, or less flexibility, thereby to conform to the characteristic utilized in my invention.

The functions of the intermediate portion of increased rigidity of the matrix band are, first, to keep this portion of the band from being pulled through the interstice between adjacent teeth, such as 1 and 2 in Fig. 1, and secondly, to assist, by the preferred trapezoidal shape of the portion of increased rigidity, in the foreshortening of the band along the edge to be disposed adjacent the gingival line. The folded-over portion 23 may be thought of as merely adding to the band at

its intermediate portion sufficient bulk to prevent the intermediate portion from being pulled through the interstice between teeth 1 and 2. It may be thought of, alternatively, as a separate member interposed between the intermediate portion of the band and the interstice having a bulk sufficient to maintain the intermediate portion from pulling through the interstice. It may also be thought of as being a part of the band to make the band stiff through a length great enough to bridge the interstice, or it may be considered as a separate member attached to the band and being characterized by sufficient stiffness and length not to pass through the interstice. A great many other ways of providing bulk or stiffness to perform the necessary function will be apparent to those skilled in the art.

The ear portion 24 of the clip 10 is useful in further tending to maintain the band closely along the tooth face, and as heretofore explained it is preferably bent or curved to approximate the shape of the tooth. Ear portion 24 of clip 10 and ears 11, 12, 13 and 14 of members 7 and 8 are all preferably of a somewhat ductile and resilient metal to permit bending thereof as with pliers and slight self-adjustment, because of the resilience, as the band is tightened in place. It is thus possible to obtain a close fit of the band to the teeth regardless of the shape of the teeth in any particular instance. It is to be assumed, of course, that different sizes and shapes of matrix bands and of clips will be used for the several distinct types and sizes of teeth, wider bands being used for longer teeth and longer clips for wider spaced teeth, and the like.

The instrument is shown in Fig. 5 partially in cross section taken along the line 5—5 of Fig. 1. Fig. 5 discloses additional details of the interrelation of the parts of the instrument, and particularly the manner in which matrix band 4 extends behind tooth 2 and into the end of clip 10, the clip, as heretofore explained, performing the function of providing a stiff or enlarged intermediate portion of the matrix band. The position of cap 16 on matrix band-end-holding member 8 is also readily apparent in this view. Additional reference numerals are applied to Fig. 5 to designate, for purposes of orientation, the portions of the instrument heretofore described in connection with Figs. 1 through 4, and these hereinabove descriptions are applicable to the parts of Fig. 5.

Many of the details of the instrument heretofore described are best understood by reference to the exploded view of the instrument shown in Fig. 6. It will be immediately apparent that rod 9, including knobs 17 and 18 and sleeve 19, is omitted from Fig. 6 for the sake of clarity.

As shown in this figure clip 10 comprises a generally rectangular sheet of metal having one end or edge cut out to form ear portions 24 and 25. These ear portions are turned upwardly from the bottom edge of the clip and a flap 23 is formed by turning downwardly the upper portion of the clip. The body or outer portion 22 remains substantially vertical, and when the clip is in position on matrix band 4, the portion 22 remains on the outer face of the band while flap 23 is folded over to lie against the inner face. Ear portions 24 and 25, of course, extend further inwardly than flap 23.

The central or intermediate portion 26 of matrix band 4 is maintained by clip 10 in straight or slightly rounded shape. The portions between this immediate portion 26 and the respective end

portions 5 and 6 are adapted to extend through the interstice between a pair of proximal teeth and to conform with the confronting sides of the respective teeth in connection with which the instrument is to be used. In attaching the matrix band to the movable members 7 and 8, end portion 5 is wrapped about leg 20 of member 7 and end portion 6 is wrapped about leg 27 of member 8. The band thus extends from a point 10 on the outer surface of a leg 20, around the end of leg 20 which is remote from ear 11, along the inner side of leg 20 between the leg and the central barrel portion 28 of member 7, and thence through the slot separating leg 20 and ear 11. 15 End portion 6 is similarly wrapped about leg 27 of member 8 to extend between leg 27 and the central barrel portion 29, and thence through the slot between leg 27 and ear 13. Caps 15 and 16, which are in the nature of ferrules, are slipped over the ends of members 7 and 8, respectively, to prevent end portions 5 and 6 from becoming unwrapped from their respective legs 20 and 27 and further to lessen the danger of injury to the mouth of the patient from the sharp corners of 25 the band-end-holding members if these members were not so covered. Each of the caps or ferrules 15 and 16 comprises a hollow member, which may be formed, for example, from a section of metal tubing, the metal of the tubing being preferably of stainless steel. The tubing is shaped to conform approximately to the leg portions of members 7 and 8, and the remote ends of the caps may be closed by a metal plate, such as the plate 30 of cap 16, through which a hole 35 31 may be drilled to permit the passage therethrough of the threaded actuating rod heretofore described. Caps 15 and 16 are proportioned substantially to cover legs 20 and 27 but to leave ears 11, 12, 13 and 14 exposed. It is preferred 40 that the ears remain exposed to press band 4 against the teeth.

It will be apparent from an inspection of the general characteristics of the instrument as disclosed in Figs. 1 and 6 that it is reversible. While Fig. 1 shows the instrument as applied to a pair of teeth in the lower left or upper right jaw section, the instrument may be easily arranged for use in connection with teeth in the lower right or upper left jaw by removing caps 15 and 16, sliding end portions 5 and 6 upwardly off of legs 20 and 27 respectively, and by turning around matrix band 4 with clip 10 attached, in the position in which end portion 5 can be wrapped around leg 32 of member 8 and end portion 6 wrapped around leg 21 of member 7. Caps 15 and 16 should then be replaced, of course. After the matrix band is thus reversed, ears 12 and 14 of members 7 and 8, respectively, will be effective to press matrix band 4 into proper conforming relation to teeth of the lower right or upper left jaw and ears 11 and 13 will not be used.

In the foregoing discussion it is assumed that the rod 9 and holding members 7 and 8 are disposed on the buccal side of the teeth. This is not necessary, and it may be found desirable under certain circumstances to arrange the instrument with the rod and holding members on the lingual side and the intermediate portion, with clip 10, on the buccal side. This is particularly desirable when the band is arranged for filling the back molars, including the wisdom teeth.

It will be apparent that more or less slant in the slots between ears 11 and 13 and respective legs 20 and 27 may be desired for properly holding the band in position in respect to teeth more

or less slanting from the gingival line to the occluding edges. Similarly, clip 10 may be substantially shorter along the top, as best seen in Fig. 2, or it may be of rectangular or other shapes best to suit the particular situation.

The ears 24 and 25 of clip 10, shown in Fig. 6, are, like ears 11, 12, 13 and 14, preferably bendable with pliers and slightly resilient to provide an effective alignment of the matrix band along the teeth.

Fig. 7 illustrates a modification of the instrument in respect to one of the band-end-holding members, designated generally 33, which comprises ears 34 and 35 and legs 36 and 37, each of which is similar to and performs the function of the respective ears and legs of members 7 and 8 heretofore described. The central barrel portion 38 of the modified member 33, however, is not internally threaded but comprises a smooth bore in which a smooth unthreaded portion 39 of rod 40 is free to rotate. The threaded portion of rod 40 carries only a right hand, or left hand, thread and a member similar to member 8 of Fig. 1 is mounted thereon to approach and to be moved away from the unthreaded portion 39 in response to rotation of rod 40.

Rod 40 terminates at one end in a knob or boss 41, at or near the remote end of the smooth portion 39, and the barrel portion 38 of member 33 has a cut out transverse slot 42 cooperating with the knob 41 to maintain member 33 in fixed position along the rod while permitting free rotation of the rod with respect to member 33. Turning the rod, accordingly, moves a member such as member 8 of Fig. 1 along the rod toward or away from member 33, the ends of a matrix band being held by these respective members as in Fig. 1.

A further modification applicable to the invention is shown in Fig. 8, which comprises a modified clip 43 for use with the matrix band of Figs. 1 through 6.

In this modification the clip is formed of a single strip of metal, or other stiff material, shaped into a flattened frustoconical configuration to impart to the intermediate portion of a matrix band, such as portion 26 of band 4 seen in Fig. 6, when clip 43 is placed inside this portion, approximately the same shape as that shown in Figs. 1, 2, 4 and 5. The clip 43 is readily removable and convenient to use first with one band and then another, without unfolding of the clip as necessary with clip 10 heretofore described. Clip 43 is simple in construction and is also adapted for soldering to the intermediate portion of a band.

Cuts 44 and 45 of clip 43, near the ends thereof, separate ear portions 46 and 47 which may be bent into the position and shape best suited to a particular pair of teeth, and these ears are preferably resilient to be, to at least a small degree, self-adjusting, as with the ears of the band-end-holding members and the ears of clip 10.

Clip 43 comprises, in use, a member too large or bulky to pass through the interstice between proximal teeth, and since it is to be located between the intermediate portion of a matrix band and such interstice, it prevents the intermediate portion of the band from being pulled through such interstice.

In use, the instrument as shown in Figs. 1 through 6, unmodified or modified in accord with Fig. 7 or 8, is positioned with the threaded rod on one side of the teeth and the clip 10, or clip 43, on the other, with the matrix band between the clip and band-end-holding members extend-

ing through the interstice between the proximal teeth, of which one is to be filled for example. Turning the rod moves apart the band-end-holding members and separates ends 5 and 6 of the band. The resultant band tension pulls the clip tightly up against the teeth on the one side of the tooth line and the holding members against the teeth on the other. The band is thus caused to hug the teeth, not only through the interstice but for some distance along the lingual and buccal faces as well. The ears of the clip and of the holding members, when properly adjusted, assist in this respect and tend to extend the effective coverage by the band of the side areas of the teeth.

It will be recognized, too, that the tension of the band will tend to separate the teeth. This action is of substantial importance, for after the filling is completed, the band may be readily removed from the wide interstice without damage to the filling at the important occlusal edge, since the teeth remain separated for a short time after the rod is turned to release the tension on the band.

As so used, it will be seen that the band is held against the side of a tooth, such as tooth 1, having a cavity, such as cavity 3, by the combined action of the enlarged portion of the band, represented by the clip 10, which maintains this portion of the band against being pulled through between teeth 1 and 2, and of the member 7 which pulls end portion 5 of the band along the buccal face of tooth 1 away from tooth 2. Tooth 2 may be thought of as an anchor against which the instrument pushes with a force determined by the tension of the band. An equal force is applied to the portion of the band contacting tooth 1 through clip 10 at the lingual side of tooth 1 and through member 7, to end portion 5, at the buccal side of tooth 1. The tension thus imposed on the band to force it against that side of tooth 1 which faces tooth 2 permits the use of a flexible band which is caused closely to conform to the contour of this side of the tooth and which is thus firmly held in position to permit a filling to be pressed hard into the cavity without danger of the filling material leaking or oozing out past the retaining wall constituted by the matrix band.

While I have shown only certain preferred embodiments of my invention by way of illustration, many modifications will occur to those skilled in the art, and I therefore wish to have it understood that I intend, in the appended claims, to cover all such modifications as fall within the true spirit and scope of my invention.

What I claim as new and desire to secure by Letters Patent of the United States is:

1. A dental matrix instrument for use with a tooth comprising a side confronting a proximal tooth separated therefrom to form an interstice, said instrument comprising a flexible matrix band positionable against said side and sufficiently long to extend beyond both ends of said interstice, and means to force the extending portions of said band along the buccal and lingual sides, respectively, of said first tooth away from said proximal tooth, said means comprising slotted band end holding means, said last means having a curved protruding portion adjacent said slot engaging said band to urge said band into conformance and engagement with said first tooth adjacent the gingival line.

2. A dental matrix instrument for use with a tooth comprising a side confronting a proximal

tooth separated therefrom to form an interstice, said instrument comprising a flexible matrix band positionable against said side and sufficiently long to extend beyond both ends of said interstice, and means to force the extending portions of said band along the buccal and lingual sides, respectively, of said first tooth away from said proximal tooth, said means comprising a first member attached to one of said extending portions at one of said two last mentioned sides of said first tooth, a second member at the other of said two sides holding said other extending portion spaced from said proximal tooth, and force applying means to tension said first member away from said proximal tooth, each of said members having a portion protruding inwardly therefrom and engaging said respective extending band portions to urge said extending portions into hugging relation respectively with said buccal and lingual sides of said first tooth.

3. A dental matrix instrument for use with a tooth, comprising a side confronting a proximal tooth separated therefrom to form an interstice, said instrument comprising a matrix band positionable against said side and sufficiently long to extend beyond both ends of said interstice, and means to force the extending portions of said band along the buccal and lingual sides, respectively, of said first tooth away from said proximal tooth, said means comprising a first member attached to one of said extending portions at one of said two last mentioned sides, a second member at the other of said two sides holding said other extending portion spaced from said proximal tooth, adjustable force applying means to force said first member away from said proximal tooth along said one side, and band means extending through said interstice bearing on said proximal tooth to serve as an anchor for said second member and said force applying means, said band means comprising a continuous portion of said matrix band.

4. A dental matrix instrument comprising a flexible matrix band having an intermediate portion of substantially reduced flexibility and two ends, and adjustable tensioning means engaging said ends adjustably to pull apart said ends, thereby to tension said band.

5. A dental matrix instrument comprising a flexible matrix band having two ends and an intermediate portion separated from said ends, stiffening means attached to said portion, and means adjustable to separate said ends.

6. A dental matrix instrument comprising a flexible matrix band adapted to extend through the interstice between proximal teeth, said band having an enlarged portion of greater thickness than the width of said interstice adapted to be disposed on one side of said proximal teeth and having an end portion to be disposed on the other side of said proximal teeth, and means to pull said end portion in the direction from said interstice along said other side of one of said proximal teeth.

7. A dental matrix instrument, comprising a flexible matrix band having two ends and an intermediate portion separated from said ends by portions adapted to extend through the interstices between a pair of proximal teeth and to lie against respective confronting side faces of said teeth, said band being adapted for the disposition of said ends on one side of the tooth line and said intermediate portion on the other side, said intermediate portion being character-

ized by a bulk greater in size than said interstice thereby not to pass therethrough, and adjustable tensioning means on said one side of said tooth line connected to said ends and operative to pull apart said ends and thereby to tension said band.

8. A dental matrix instrument, comprising a flexible matrix band having two ends and an intermediate portion separated from said ends by portions adapted to extend through the interstice between a pair of proximal teeth and to lie against respective confronting side faces of said teeth, said band being adapted for the disposition of said ends on one side of the tooth line and said intermediate portion on the other side, said intermediate portion having sufficient stiffness through a length greater than the distance across said interstice to prevent said intermediate portion from passing through said interstice, and adjustable tensioning means connected to said ends and operative to pull apart said ends and thereby to tension said band.

9. A dental matrix instrument, comprising a flexible matrix band having two ends and an intermediate portion separated from said ends by portions adapted to extend through the interstice between a pair of proximal teeth and to lie against respective confronting side faces of said teeth, said band being adapted for the disposition of said ends on one side of the tooth line and said intermediate portion on the other side, adjustable tensioning means connected to said ends and operative to pull apart said ends, and means to maintain said intermediate portion on said other side of said tooth line.

10. A dental matrix instrument, comprising a matrix band having two ends and an intermediate portion separated from said ends by portions adapted to extend through the interstice between a pair of proximal teeth and to lie against respective confronting side faces of said teeth, said band being adapted for the disposition of said ends on one side of the tooth line and said intermediate portion on the other side, means to separate said ends, and means to maintain said intermediate portion on said other side of said tooth line, said last means comprising a member disposed between said intermediate portion and said interstice.

11. A dental matrix instrument, comprising a matrix band having two ends and an intermediate portion separated from said ends by portions adapted to extend through the interstice between a pair of proximal teeth and to lie against respective confronting side faces of said teeth, said band being adapted for the disposition of said ends on one side of the tooth line and said intermediate portion on the other side, means to separate said ends, and means to maintain said intermediate portion on said side of said tooth line, said last means comprising a member disposed between said intermediate portion and said interstice and having a portion cooperating with said band to maintain a part of said band against a part of one of said teeth.

12. A dental matrix instrument comprising a flexible matrix band, a stiffener member engaging an intermediate portion of said band, first and second band-end-holding members detachably secured to respective ends of said band, and means comprising a threaded rod to separate said ends, at least one of said holding members comprising a threaded portion engaging the threads of said rod.

13. A dental matrix instrument comprising an

11

elongated, flexible, metallic matrix band, a retaining member affixed to the intermediate portion of said band, said member being proportioned and arranged to be held by proximal teeth against passing through the space between said proximal teeth, said band having operative portions extending from said member and terminating in respective end portions remote from said member, two end-holding-members detachably engaging respectively said end portions, at least one of said members being threaded, and threaded means cooperating with said threaded member to adjust the separation of said end portions.

14. A dental matrix instrument for use in connection with a defective tooth having a second proximal tooth separated therefrom to define an interstice therebetween, said teeth defining a tooth line presenting a buccal side and a lingual side for said teeth; said instrument comprising an elongated flexible matrix band, a rod threaded through at least part of its length and carrying two band-end-holding members, at least one of said members being threaded to cooperate with the threads of said rod and to be moved therewith in response to rotation of said rod, the other said member being provided with means cooperating with a portion of said rod to prevent said other member from following said first member when said rod is rotated, an intermediate portion of said band being proportioned to present sufficient bulk not to pass through said interstice and being adapted for positioning adjacent one of said sides beyond one end of said interstice, said band having two portions extending from respective opposite ends of said intermediate portion which are adapted to extend side by side through said interstice and which have

12

terminal portions to extend beyond said interstice adjacent the other said side, said terminal portions being detachably connected respectively to said members, said rod and members being adapted to be disposed adjacent said other side.

15. A dental matrix instrument comprising a flexible matrix band adapted to extend through the interstice between proximal teeth, said band having an enlarged portion of greater thickness than the width of said interstice adapted to be disposed on one side of said proximal teeth and having an end portion to be disposed on the other side of said proximal teeth; and means to pull said end portion in the direction from said interstice along said other side of one of said proximal teeth, said means comprising a band end holding device having a slot to receive said band, said slot being inclined to the vertical upwardly toward said interstice whereby said band in said interstice hugs the lower portion of said one tooth adjacent the gingival line.
